UNITED STATES PATENT OFFICE.

LOUIS DURAND, OF DUMONT, NEW JERSEY, ASSIGNOR TO THE AMERICAN EXCHANGE NATIONAL BANK OF NEW YORK, A CORPORATION.

DOUGH-KNEADING MACHINE.

SPECIFICATION forming part of Letters Patent No. 760,388, dated May 17, 1904.

Application filed September 8, 1902. Renewed August 4, 1903. Serial No. 168,204. (No model.)

To all whom it may concern:

Be it known that I, LOUIS DURAND, a citizen of the United States, and a resident of Dumont, in the county of Bergen and State of New Jersey, have invented certain new and useful Improvements in Dough-Kneading Machines, of which the following is a specification.

This invention relates to that class of dough-making machines which are presented in the form of small machines adapted for family use and which involve a horizontally-rotatable pan containing a stirrer and kneader revoluble on separate axes, an illustration of such type of machine being disclosed in my Patent No. 485,096, dated October 25, 1892.

The principal objects of the present invention are the simplification of the construction generally, increased convenience and efficiency of operation, as well as facility for cleaning the pan, stirrer, and kneader, and the location of both the stirrer and kneader gearing external to and above the pan.

There are other important structural features connected with the improved dough-machine which, in addition to those alluded to, are clearly set forth in the subsequent detailed description.

In the accompanying drawings, forming part of this specification, Figure 1 represents, in side elevation and partly in section, the improved dough-making machine adjusted on the end portion of a table-top. Fig. 2 is a plan view of the machine as adjusted in Fig. 1. Fig. 3 is a detail view, partly sectioned, and disclosing in elevation certain bevel-gear bearings detached from the frame designed for the support thereof. Fig. 4 is an outer end view of the kneader-blade.

Similar reference characters are employed to designate corresponding parts in the several figures wherein they occur.

The pan A has a central vertical cone a', provided with a lower interior bridge a² and upper hub h, in the lower end of which latter is secured the upper end of a vertical shaft a, centrally located within the cone and bearing in and preferably connected to the bridge, the extremity of the shaft below said bridge

being stepped in the bearing b, on the upper horizontal clamping member B' of the supporting-frame B, which is provided with the under member carrying the clamping-screw B².

Mounted on a small platform at the upper end of the frame B is a part C, provided with bearings for the primary elements of the operating-gear, said part being attached in position through the medium of bolts d d', pivotally secured on the under side of the platform and adapted to be swung up to engage and be clamped between lugs e e', presented by the base of the part C, and also by the platform.

The part C overhangs the pan to a considerable extent and carries at its inner end a shallow horizontal casing C', a portion of which is over the vertical center of the pan, while the other portion of the casing is disposed radially at the side opposite to that at which the part C is located. This casing at the point of a bottom bearing g rests loosely upon the hub h, a combination bevel and spur gear D within the casing being rigidly secured on a stub-shaft f, depending through said bearing and provided with a square lower end engaging with the corresponding-shaped upper part of the socket within said hub. The spur part of the gear D meshes with the spur-gear F in the radial portion of the casing, said gear F being secured on the upper end of a vertical shaft j, turning loosely in an extended tubular bearing C², suspended from the under side of the casing. On the lower extremity of the shaft j at the end of the bearing is secured the stirrer-blade G of open character and of such dimensions that its outer downwardly-converging edges will move in close parallel relation both with the exterior of the cone and inner surface of the pan side.

The beveled portion of the gear D meshes with a driving-pinion H, secured on the inner end of a shaft k, extending through the casing-wall and projecting a short distance within the casing interior, said shaft being revolvably contained in an elongated horizontal bearing C³, integrally carried by the part C, the other end portion of the shaft extending be-

yond the outer end of said bearing for the 5
securement of an operating-crank J and bevel-
pinion K, the latter meshing with a bevel-
gear L on the upper end of an inwardly-in-
clined shaft s, mounted in a correspondingly-
inclined bearing C⁴, also integrally carried by
the part C and normally disposed at one side
10 of the main or vertical portion of the frame
B. Secured on the lower projecting end of
the shaft s is the kneader P of open character
and provided with angularly-disposed ex-
tended straight edges p p' p', adapted to
15 alternately move into and out of close parallel
proximity with respect to the cone exterior
and inner surface of the pan side at certain
points thereof.

At suitable points along the upper edge of
the vertical wall of the casing C' are portions
20 c, having openings tapped for the reception
of bolts designed to secure a cover C⁵ upon
the casing, said casing being arched to pro-
vide clearance for the hub of the wheel F and
upper end of the shaft j and also for the loca-
25 tion of an under bearing c' for receiving
the upward thrust of the shaft a and con-
tributing to support it in position.

In operating the machine motion is imparted
to the shaft k by the crank J, causing the pan
A to revolve in a horizontal plane, the motion
30 thus acquired being transmitted to the shaft
j to revolve the stirrer G in a direction oppo-
site to that of the pan. Coincidently the shaft
s is rotated through the medium of the bevel-
gearing K L and rotates the kneader P also
35 in a direction opposite to the pan movement.
The stirrer effects the proper mixing of the
material within the pan, while the kneader
overturns and kneads such material. The pec-
uliar disposition of the edges p p' of the
40 stirrer causes them to move into and out of
close parallel relation with the cone and pan
side, thus promoting the proper shifting of
the material and preventing the undesirable
lodgment at either of said points. When the
45 batch of dough is properly developed, the
clamp-bolts d d' are loosened and swung out
of engagement with the lugs e, whereupon the
part C, together with the casing C' and all the
50 gears and other features carried by said part
and casing, can be completely removed from
position, leaving the pan, with its dough,
convenient for the removal of the latter and
subsequent cleaning of the pan. The discon-
55 nection of the part C and casing C' also greatly
facilitates the cleaning of the stirrer and
kneader blades. For further use the part C
and casing C', with their appurtenances, are
restored to their former positions and securely
held by the adjustment of the bolts d d'.
60 It will be appreciated from the foregoing
description that the improved machine is not
only simple and durable, as well as highly use-
ful, but that it can when required be readily
taken apart and cleaned. Furthermore, with
65 the exception of the unobjectionable arrange-

ment of the shaft a and the stirrer and kneader,
all the moving and operating parts are out-
side of the pan.

Having now described my invention, what
I claim as new, and desire to secure by Letters
70 Patent, is—

1. In a dough-making machine, the combi-
nation with a pan and a juxtaposed frame, of
a part detachably connected to the frame and
carrying conjointly a stirrer and kneader, both
75 within the pan, and stirrer and kneader actua-
ting means including gearing also carried
by said part, said gearing being entirely out-
side of the pan.

2. In a dough-making machine, the combi-
nation with a pan and a juxtaposed frame, of
a part detachably connected to the frame and
carrying conjointly a stirrer and kneader, both
85 within the pan, stirrer and kneader actua-
ting means including gearing also carried by
said part, said gearing being entirely out-
side of the pan, and provision operable from
said actuating means for horizontally rotat-
ing the pan.

3. In a dough-making machine, the combi-
nation with a pan and a juxtaposed frame, of
a part detachably connected to the frame and
carrying a kneader, the latter within the pan,
a casing above the pan and carried by and re-
90 movable with the said part, a stirrer suspended
from said casing, and stirrer and kneader actua-
ting means also supported by said part and
including gearing within the casing for re-
volving the stirrer, all of the said actuating
100 means as well as the casing and its gearing
being entirely outside of the pan.

4. In a dough-making machine, the combi-
nation with a horizontally-rotatable pan, its
central shaft, and a juxtaposed frame, of a
part detachably connected to the frame and
carrying a kneader, the latter within the pan,
a casing above the pan and carried by and re-
105 movable with the said part, a stirrer suspend-
ed from said casing, and stirrer and kneader
actuating means also supported by said part
and including gearing within the casing for
revolving the stirrer and pan-shaft, all of said
110 actuating means including the casing and its
gearing being entirely outside of the pan-
shaft.

5. In a dough-making machine, the combi-
nation with a pan and a juxtaposed frame, of
a part carrying a kneader, stirrer and operating
means therefor, and including gearing inde-
pendently of both the pan and frame, all of said
120 operating means being entirely outside of the
pan, and the said part being supported by a
detachable connection with the frame.

6. In a dough-making machine, the support-
ing-frame and part C removable therefrom,
125 the pan with the center cone and upper hub
and shaft a, extending above the top of the
pan under the casing C', and arranged to lock
with the shaft f, together with suitable oper-
ating means carried by the part C.

7. In a dough-making machine, the combination with a pan and supporting-frame, of the part C, provided with an angle-bearing and shaft s, the latter carrying an angle-
5 stirrer P, operable by a bevel-gear attached to the shaft s, outside of the supporting-frame and engaging with a bevel-pinion on a driv-
ing-shaft also carried by the part C.

8. In a dough-making machine, the combi-
10 nation with the revoluble pan, and part C, a shaft supported by said part C, and having a beveled driving-pinion, a combined bevel and spur gear D, with the bevel portion of which said pinion meshes, a spur-gear meshing with

the spur portion of the gear D, a stirrer actu-
ated by said spur-gear, a casing entirely out-
side of the pan, and supported by the part C,
and containing said beveled driving-pinion,
bevel and spur gear D, and spur-gear, and
means also outside of the pan for imparting 20
motion to the gearing and stirrer.

Signed at New York, in the county of New York and State of New York, this 5th day of September, A. D. 1902.

LOUIS DURAND.
